Primary Examiner—Alan P. Douglas*Assistant Examiner*—R. Spear*Attorney, Agent, or Firm*—Phillips, Lytle, Hitchcock, Blaine & Huber[57] **CLAIM**

An ornamental design for a package for a football shaped object, as shown and described.

DESCRIPTION

FIG. 1 is a perspective view of the package for a football shaped object showing my new design;
FIG. 2 is a top plan view of the package for a football shaped object;

FIG. 3 is a bottom plan view of the package for a football shaped object;

FIG. 4 is a side elevation of the package for a football shaped object, the opposite side elevational view being a mirror image thereof; and,

FIG. 5 is an end plan view of the package for a football shaped object, the opposite end elevational view being a mirror image thereof.
